UNITED STATES PATENT OFFICE.

BALLARD R. SMITH, OF RUSH RUN, WEST VIRGINIA.

CAR-COUPING.

SPECIFICATION forming part of Letters Patent No. 576,233, dated February 2, 1897.

Application filed June 30, 1896. Serial No. 597,634. (No model.)

To all whom it may concern:

Be it known that I, BALLARD R. SMITH, a citizen of the United States of America, residing at Rush Run, in the county of Fayette 5 and State of West Virginia, have invented certain new and useful Improvements in Car-Couplings; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of my invention is to provide an improved automatic car-coupling of the hook-and-link type, which is more especially adapted for use in connection with mining-cars, the hook and link being so constructed and 20 connected to their respective draw-bar that they will be maintained in a normally horizontal position and will be capable of an upward swinging movement, the link being arranged to project horizontally from the draw-bar, while the hook is so shaped that a portion of the same will be positioned below the 25 level of the link in order that when the cars come together the link will be lifted to be free to move over the end of the hook.

30 My invention consists in providing a car with a continuous draw-bar, to one end of which is connected the hook and to the other end the link, said draw-bar being bolted to the floor and transverse beams of the car.

35 The invention further consists in the construction and arrangement of the bumpers, between which the coupling device is located, said bumpers being practically a continuation of the floor of the car.

40 The invention further consists in the construction and combination of the parts, as will be hereinafter fully set forth and claimed.

In the accompanying drawings, forming 45 part of this specification, Figure 1 is a plan view of the coupling, the hook and link being shown in engagement with each other. Fig. 2 is a side elevation of the hook, the link being shown in section and elevated in dotted lines. Fig. 3 is a plan view of one of the cars. Fig. 4 is a longitudinal sectional view.

A designates the car-body, which is provided with bolsters of the usual type, to which

is secured the floor A', said floor extending beyond the ends of the body to present projecting portions a a, serving as bumpers. 55 Upon the floor is located a draw-bar B, which is bolted or otherwise secured to the floor of the car. Each end of this draw-bar is bent upon itself and cut away centrally to present loops or eyes C C, the terminal of the draw-bar being extended to lie under the ends of the floor of the car. It will be noted that the part of the draw-bar between the eyes C provides bearings which serve to maintain the hook and link in a normally horizontal position, the said hook and link being constructed for this purpose, as hereinafter described.

D designates the link, which is made up of a single bar of metal bent or formed to present side members and a forward connecting 70 portion, the rear ends being bent inward to engage the eyes C, while the terminals are bent forwardly between said eyes to provide a secure connection, as well as to bear upon the part of the draw-bar between the eyes, 75 for the purpose hereinbefore stated.

E designates the hook, which is also made up of a bar of metal shaped to form the hook proper and the ends bent to engage the eyes C and extend forward between the same in 80 a manner similar to the link and for the same purpose. The hook proper is bent downward, as shown, so as to locate the forward part thereof slightly below the plane of the link in its normal position. By this arrangement the link will ride upon the inclined portion of the hook and cause an automatic coupling of the cars when they come together.

The hook and link can be thrown back out of operative position by simply swinging the 90 same back against the car-body or cross-piece thereof.

It will be noted that the bumpers extend sufficiently forward so that when the cars come together the hook nor the link will not 95 contact with the ends of the draw-bar, and when the cars are coupled the usual swing or play will be allowed in rounding a curve, as is provided by the ordinary pin-and-chain coupling used upon cars of this character. 100

Having thus described my invention, what I claim as new, and desire to secure by Letters Patent, is—

1. A coupling for mining-cars, comprising

a link and a hook, draw-bars having eyes by which the hook and link are connected thereto and a bearing-surface between said eyes, the hook and link being provided with portions which extend forward between the eyes of the draw-bar, substantially as shown and for the purpose set forth.

2. In a coupling for mining-cars, the combination, of the continuous draw-bar the ends of which are bent upon themselves or looped and cut away centrally to present eyes with a bearing-surface between; together with the hook and link having their ends bent to engage the eyes and their terminals extended forward, substantially as shown and for the purpose set forth.

3. In a coupling for mining-cars, the combination, of a continuous draw-bar having terminal portions bent upon themselves and cut away centrally to present eyes C C; to-

gether with a link the ends of which engage with the eyes C of the draw-bar, and a hook similarly connected to the other end of the draw-bar, substantially as shown and for the purpose set forth.

25

4. In a mining-car, the combination, of the continuous draw-bar having its ends bent as shown, a hook and a link connected to said bent ends; and the floor of the car extended at its ends on each side of the coupling devices to provide bumpers a a, the said bumpers projecting sufficiently to prevent the hook and link from engaging with the ends of the draw-bar when the cars come together.

30

In testimony whereof I affix my signature in presence of two witnesses.

35
BALLARD R. SMITH.
